UNITED STATES PATENT OFFICE.

DORMAN E. HAMIEL, OF COLUMBUS, OHIO.

LAMP SOCKET.

Application filed February 20, 1925. Serial No. 10,702.

This invention relates to an improved socket adapted for the quick and convenient attachment of separable current conveying members and specifically, the invention provides a socket into which a separable plug or lamp base can be quickly and easily inserted and supported therein for the efficient transmission of electric energy and with an effective mechanical union between the separable parts.

It is an object of the present invention to provide a lamp socket in which the threaded base of an ordinary incandescent lamp may be inserted and secured without involving the use of screw threads, as is now customary. It is a tedious and time consuming task to insert the ordinary threaded form of incandescent lamps into the receiving sockets in which they are to be placed or mounted. In the first place there must be proper registration between the lamp base and the receiving sockets, and then the lamp must necessarily be rotated to the end of the socket to effect the necessary electrical contact between parts. It is an object of the present invention to provide a socket in which the lamp base may be inserted by a sliding movement which can be quickly and easily accomplished in but a fraction of the time required to thread the lamp in an ordinary socket, and to construct the socket so that the same will securely support the lamp therein with the same security as provided by the threaded form of socket and with equivalent electrical efficiency.

With these and other objects in view, as will appear as the description proceeds, the invention consists in the novel features of construction, combinations of elements and arrangements of parts hereinafter to be fully described and pointed out in the appended claims.

In the accompanying drawings:

Figure 1 is a vertical sectional view, partly in side elevation of a lamp socket constructed in accordance with the present invention,

Figure 2 is a horizontal transverse sectional view on the line 2—2 of Figure 1, and

Figure 3 is a perspective view of the spring tension ring.

In the accompanying drawing the socket comprising the present invention is shown as suspended from current conducting wires 2. It will be appreciated, however, that

while this type of socket has been selected for purposes of illustration, nevertheless, the features of the invention are capable of being embodied in any form of socket wherein a threaded plug or lamp base is used in connection therewith. That is, the principles of the invention are adapted to wall or floor sockets, lighting fixtures or any other form of electrical apparatus wherein it is desired to transmit electrical current through separable members.

The socket 1 illustrated includes the usual body 3 of insulation and includes a central contact 4 and spaced or insulated return contacts 5, the contacts 4 and 5 being in communication and secured to the wires 2 in any suitable manner.

Surrounding the body 3 is a metallic sleeve 6 in which is positioned a tube 7 of insulating material, and arranged to be carried by and connected with the contacts 5 are separable threaded supporting wings 8, formed from metal so as to be in electrical communication with the contacts 5.

It is customary to provide a socket of this character with an internally threaded metallic bushing or sleeve in which is threaded the base 9 of an electric lamp 10 or other electrical apparatus. However, in the present invention such a threaded bushing is eliminated and in place thereof the resiliently separable wings 8 are provided. These wings are permitted to flex about the plane defined by their points of connection with the contacts 5 and sufficient space is provided between said wings and the tube 7 to permit of this function. By this construction the lamp base 9 may be inserted directly into the socket by a straight, inwardly directed linear movement, the wings expanding or separating as a threaded portion of the base 9 engages with the corrugations or threads of the wings 8, so that when the central contact 11 of the base 9 engages with the contact 4, the wings will exercise a frictional grip upon the base 9 to support the latter within the socket.

An important feature of the present invention resides in supplementing the normal or inherent resiliency of the wings 8 with a surrounding spring ring or collar 12. This ring or collar is positioned within an annular recess 13 provided in the sleeve 6 and tube 7 near the open lower end of the socket. The ring or collar comprises a band of sheet metal bent or corrugated as indi-

cated in Figure 3, and the position of said ring is such that its normal tendency is to hold the wings in their nearest positions of relative approach, so that the same will 5 exercise a reinforced maximum securing grip upon the base 9, preventing the latter from becoming accidentally disengaged with the wings 8 as will be apt to happen were not the ring or collar 12 provided. It 10 will be seen, however, that by reason of the corrugations in said ring the said wing sections 8 may separate sufficiently upon the removal or insertion of the base or plug 9 to permit of longitudinal travel thereof 15 in the socket 1, but when such travel has ceased the wing sections will be moved relatively toward each other to exercise a secure grip on the base 9.

In view of the foregoing it will be seen 20 that the present invention provides a simple, convenient and effective fixture by means of which separable current conducting members can be readily connected together or taken apart and wherein provision is present 25 ent for effecting the mechanical support of said members as a unit. The socket does not in any way change the standard form of lamp base, or other threaded fixture now in general use and of accepted design. The 30 construction is particularly useful where it is necessary at frequent intervals to remove

the lamps from or insert the same into sockets or fixtures, so that this operation can be carried out quickly, efficiently and with but slight loss of time.

35

What is claimed is:

1. An incandescent lamp holder comprising a base, an outer metallic sleeve carried by the base and forming a socket for the removable reception of a lamp base, said sleeve being provided with an angular spring seat, a split lamp base receiver carried by the base and arranged within said socket, and an annular spring confined between the sleeve and the receiver and positioned in said seat for coaction with said receiver to resiliently resist expansion on the part of the receiver.

40

2. An incandescent lamp holder comprising a base, an outer metallic sleeve carried by the base and forming a socket for the removable reception of a lamp base, said sleeve being provided with an angular spring seat, a split lamp base receiver carried by the base and arranged within said socket, and an annular corrugated spring confined between the sleeve and the receiver and positioned in said seat for coaction with said receiver to resiliently resist expansion on the part of the receiver.

45

In testimony whereof I affix my signature.

DORMAN E. HAMIEL.
